AUTOMATIC TUNING DEVICE FOR RADIO RECEIVERS

Howard A. Gates, Detroit, Mich.

Application February 26, 1937, Serial No. 127,972

5 Claims. (Cl. 116—124.1)

This invention relates to radio receivers and has particular reference to an automatic tuning device for such receivers.

An object of the invention is the provision of an automatic tuning device which is simple in construction, inexpensive to manufacture, and easily attached to an ordinary radio receiving set.

Another object of the invention is the provision of an automatic tuning device for radio receivers which is extremely accurate in its functioning after it is once set.

Another object of the invention is the provision of a device of the character referred to which may be readily attached and adjusted for automatic tuning by a layman without the necessity of using special tools or equipment.

Another object of the invention is the provision of a device of the character referred to which may be used to automatically tune in the maximum number of stations on a radio receiver.

A further object of the invention is to generally improve tuning devices for radio receivers by the provision of mechanical means for accurately logging stations for an individual radio set and mechanical means for re-locating said stations after the same have been logged.

The foregoing and other advantages and objects will appear as the description proceeds, reference being made to the drawing, in which:

30 Fig. 1 is a fragmentary front elevation, with parts broken away, illustrating my device as being attached to a conventional radio receiver.

Fig. 2 is a section taken on line 2—2 of Fig. 1.

Fig. 3 is a front elevation, with parts broken away, of the rotatable member carrying the stylus.

Referring now more particularly to the drawing, it will be seen that I have illustrated my invention in position on a conventional radio receiver, wherein 5 indicates the cabinet and 6 (Fig. 2) represents the plates of a tuning condenser.

The principal elements of my invention are arranged to be supported upon the shaft 7, and the body of the tuning condenser, and the front 45 wall 8 of the cabinet 5, in the manner described more particularly hereinafter.

The conventional dial 9 (Fig. 2) of the radio receiver is supported in a dish-shaped stamping 10, the edges of which are rolled as at 11 to form 50 a retaining rim. A spring wire retaining element 12 is positioned in front of the dial 9, and prevents the latter from being displaced from the rim 11 of the member 10. The dial supporting member 10 is held in position about the shaft 7 by means of a bushing 13 to which it is secured by

any suitable means. In this instance the edges 14 of the bushing 13 are spun over the walls of the member 10, and about the edges of the centrally disposed opening formed in the back of the member 10. The bushing 13 is secured to the 5 housing of the tuning condenser by any suitable means which holds it against rotation.

An indicator needle 15 is press-fitted onto the shaft 7 and is arranged to rotate with said shaft. Positioned in front of the needle 15 is an annular member 16, the purpose of which is explained hereinafter. The member 16 has its edges rolled as at 18 in order to reinforce it and to give it a finished appearance. A retaining element 19 is arranged to engage the inner periphery of the side 15 walls of the member 16. The member 16 is utilized for the purpose of supporting the stylus, as hereinafter explained, and is connected to the cover-plate 20 which in this instance is illustrated as being made of glass although it may be made 20 of any transparent material, to permit the dial 9 to be seen at all times. The glass cover-plate 20 is held in the annular member 16 by means of the retaining element 19. It is shock insulated by means of a cork gasket 21, which is positioned 25 between the back of the glass 20 and an offset formed in the side wall of the member 16. The member 16 is adapted to rotate with the shaft 7 of the tuning condenser. The rotation is made possible by reason of the fact that the glass cover- 30 plate 20 is connected to the shaft 7 by means hereinafter described. It will be understood that the cover-plate 20 is provided with a centrally disposed opening into which is fitted a small dish-shaped stamping 22, which has a flared rim 23. 35 A backing washer 24 is secured to the stamping 22 by means of rivets 25, and the glass cover-plate 20 is shock insulated on either side by means of cork or felt washers 26. This assembly is then secured to the shaft 7 by means of the bolt 27, 40 which is inserted in an internally threaded bore 28 positioned in the shaft 7.

At a predetermined place on the edge of the member 16, I have caused to be formed an offset 29, the latter having its edges inturned for reinforcing. The offset 29 is provided with a centrally disposed opening 30 into which is inserted, and secured by spinning or other suitable means, a small bushing 31. A second bushing 32 extends longitudinally through the bushing 31 50 and is free to slide therein. Superimposed on the bushing 32 is a hollow knob 34, the latter being arranged to cover the bushing 31 and the spring 33, which is held between the offset 29 and a corresponding offset formed in the inner 55

wall of the hollow knob 34. A pointed pin 35, which serves as a stylus as hereinafter described, extends through the bushings 31 and 32, and the hollow knob 34, and is secured against displacement by means of an enlarged shoulder at one end and riveting at the other. For the sake of brevity I will refer to this last described assembly as the stylus.

Secured to the front wall 8 of the cabinet 5 by means of small screws 36 is an escutcheon plate 37, which is primarily an annular member having a cross-section as illustrated in Fig. 2. This annular member 37, which I will refer to hereinafter as the escutcheon plate, is preferably made of a soft material such as gilder's metal or other comparatively soft metal which will take a polish or finish. The escutcheon plate 37 is arranged to carry the call letters of radio broadcasting stations as indicated by the character 38, Fig. 1. The call letters 38 may be placed on the escutcheon plate 37 by any suitable means and are positioned on the escutcheon plate 37 in such manner as to register with corresponding wave length or kilocycle calibrations, as indicated by the reference numeral 39, carried on the indicator dial 9. In the disclosure herein made the dial 9 carries long wave lengths along the top, and short wave lengths along the bottom. The reference character 40 indicates the volume and other controls on the receiver, but these have no relation to the invention, except through their ordinary functions in connection with a radio receiving set.

The purpose of the mechanism just described is to enable the user to permanently designate the predetermined positions of given stations on the escutcheon plate, so that it is a comparatively easy matter to again tune the set to a particular broadcasting station after a setting is once made. It is possible with this device to indicate on the escutcheon plate almost as many stations as it is possible to register on the dial 9 of the receiving set.

The operation of the device is very simple. After it is assembled and in position on a radio receiving set, and it is desired to fix the tuning position thereon of any given broadcasting station, the following operations are carried out.

The operator simply takes hold of the knob 34 and rotates the same about the axis 7 until the needle or pointer 15, indicates the desired tuning position of a certain station on the dial 9, for it will be remembered that the needle or pointer 15 and the member 16 are fixed to and adapted to rotate with the tuning condenser shaft 1. When the most efficient tuning position for a given station is reached, the operator then marks that position on the escutcheon plate 37 by means of the stylus 35. To do this it is only necessary to move the stylus 35 toward the escutcheon plate, and when in contact with the latter, the stylus 35 is struck with sufficient force with the hand or any instrument, so that the point of the stylus makes an indentation at the desired location on the escutcheon plate. The spring 33 tends to return the stylus 35 to its inoperative position. The corresponding letters of the broadcasting station in tune are then positioned on the escutcheon plate immediately opposite the indentation made thereon with the stylus. The proper tuning position of any desired station, whether of short or long wave length, may then be indicated

in the same manner, and when it is desired to re-tune the set to any predetermined station so marked it is a simple matter to rotate the stylus to the approximate position of the station, and then obtain an absolutely accurate re-tuning by means of feeling the point of the stylus into the respective indentation for that station theretofore made.

Because of the infinitesimal amount of room taken by the indentations on the escutcheon plate, it is possible to mark the plate for as many tuning positions as it is possible to indicate on the dial 9. With this device an amateur can mark a radio receiving set for automatic tuning thereafter without the necessity of using any special instruments and without the necessity of tearing down the set to do so.

Having described my invention, what I claim and desire to secure by Letters Patent is:

1. In combination with a radio receiver, an escutcheon plate, a non-rotatable dial carrying member, a rotatable needle, and a rotatable member synchronized with said needle, said last named member having a stylus thereon, arranged to contact said escutcheon plate, and a transparent cover member for said dial secured to said rotatable member.

2. In combination with a radio receiver having a dial and a revolving needle, an escutcheon plate adjacent said dial consisting of comparatively soft material, a member synchronized for rotation with said needle, said member having a stylus thereon made of comparatively hard material, said stylus being slidably and resiliently mounted in said member and adapted to be struck to form indentations at desired positions on said escutcheon plate.

3. In combination with a radio receiver having a fixed dial and a needle arranged to revolve adjacent said dial, an escutcheon plate adjacent said dial, a member synchronized for rotation with said needle, said member having a transparent front section through which said dial and said needle are visible at all times, and a stylus slidably secured to said member and arranged so that it may be struck to form indentations on said escutcheon plate at predetermined positions indicated by said needle.

4. In combination with a radio receiver having a tuning condenser including means for indicating various positions of said tuning condenser, an escutcheon plate adjacent said tuning condenser, a member arranged to synchronously rotate with the shaft of said tuning condenser, said member having a transparent section through which said indicating means are at all times visible and a stylus slidably secured to said member and arranged to contact said escutcheon plate.

5. In combination with a radio receiver having a tuning condenser and means for indicating the various positions of said condenser, an annular escutcheon plate surrounding said indicating means, a member mounted for synchronous rotation with the shaft of said tuning condenser, a circular transparent element concentrically mounted on said member, an annular member secured to said transparent member and a stylus secured to said annular member and arranged to contact said escutcheon plate.

HOWARD A. GATES.
